GIRDLE OR LIKE ARTICLE OF APPAREL

Henry M. Herbener, Thomasville, Ga.

Application August 12, 1939, Serial No. 289,921

6 Claims. (Cl. 2-36)

My invention relates to apparel.

An important object of the invention is to provide a fabric with a rib receiving pocket having a bottle neck leading into one end thereof, the bottle neck extending beyond the pocket so that the stitching of the edge of the fabric to a garment or the like may also close the bottle neck.

Figure 1 is a side elevation of a band secured to a garment part, the pocket being shown in section, the section being taken in the plane of the pocket.

Figure 2 is a rear perspective view of a body encircling garment embodying my invention.

Figure 3 is a horizontal section taken on line 3-3 of Figure 2.

Figure 4 is a side elevation of one of the horizontal pockets, parts in section.

Figure 5 is a plan view of one of the horizontal ribs.

Figure 6 is a perspective view of the horizontal rib.

Figure 7 is a perspective view of a modified form of horizontal rib.

Figure 8 is a front perspective view of a girdle or the like embodying a further modification of the invention.

Figure 9 is a side elevation of one of the pockets of the girdle shown in Figure 8, parts of the pocket being shown in section.

Figure 10 is a longitudinal section taken on line 10-10 of Figure 9.

Figure 11 is a fragmentary side elevation of an elastic band embodying a further modification of my invention, parts in section.

Figure 12 is a transverse section taken on line 12-12 of Figure 11.

In Figure 1, I have shown a slight modification of the elastic bands 36 of my prior Patent 2,136,742. As disclosed in my prior Patent 2,136,742, each pocket of the elastic band is woven closed at one end and provided with an opening near its opposite end which is shorter than the width of the pocket. By stretching the opening, the rib is introduced into the pocket and when the pocket is released, the opening contracts to its normal dimension and there are shoulders to hold the rib against displacement. In Figure 1, the numeral 53 designates a woven elastic band which is horizontally or longitudinally elastic and vertically non-elastic, and this band has spaced transverse pockets 55 woven integral therewith. The opposite sides of each pocket are horizontally elastic and the spaces between the pockets are horizontally elastic. The band 55 may be formed of a woven or knit material. One

end 56 of the pocket is woven closed, but the opposite end is provided with an opening 57 which is shorter than the width of the pocket to permit of the insertion of the rib 58 when the opening 57 is stretched. In Figure 1, the opening 57 is disposed at one vertical edge of the pocket, thus providing a more pronounced shoulder 59, to positively hold the rib against displacement through the opening 57. The rib 58 is provided at its top and bottom with projections or teeth 60, adapted to firmly engage or bite into the fabric, whereby when the fabric and the pocket are horizontally stretched, the rib 58 will follow the stretching action to the left, Figure 1, moving the rib from over the opening 57, which may become elongated due to the stretching action, thereby preventing the rib from being displaced through the opening 57. The opening 57 is formed by a reduced portion or bottle neck 57', which may be closed by stitching 58', also serving to attach the band to a girdle or the like. The stitching closes the opening of the bottle neck and the bottle neck has a substantial length so that the stitching will be spaced a substantial distance from the rib 58, so that there will be no liability of the needle striking the stiffening ribs when sewing the stitching 58'.

The body portion 20 of the garment or girdle shown in Figure 2, is provided in its back with an opening or space covered by a panel 61. This panel 61 is preferably highly vertically elastic but horizontally non-elastic. This panel is secured to the body portion 20 and to the band 22 by zig-zag stitching 62. The panel 61 extends from the lower band 22 to a point near the middle of the body portion 20, as shown. The panel 61 has horizontal pockets 63, Figures 3 and 4, preferably woven integral therewith and these pockets are spaced. Since the panel 61 is vertically elastic, the opposite sides of each horizontal pocket are vertically elastic and the spaces between the pockets are vertically elastic. If desired, the panel 61 may also be horizontally elastic. Arranged within each horizontal pocket 63 is a stiffening rib 64, tensioned to lie flat. The function of these stiffening ribs is to produce a flat effect in the back. In order that the free ends of the ribs 64, which tend to spring outwardly, as inward pressure or pull is applied to the panel 61, may not produce bumps or unsightly projections, I arrange a companion rib 65 upon each rib 64. The companion rib 65 is slighter than the rib 64 and therefore more flexible and resilient. The companion rib 65 has its ends extending outwardly beyond the ends of the

ribs 64 for substantial distances and the ribs 64 and 65 are attached together at their centers, as shown at 66, while the free end of one rib is capable of moving longitudinally with relation to the free end of the other rib. When the pair of ribs 64 and 65 are inserted within each pocket 63, the longer rib 65 extends for substantially the entire length of the pocket. The pocket has an off-set bottle neck 67, forming a reduced opening at one end of the pocket. The opening is shorter than the width of the pocket but the bottle neck may be stretched sufficiently to permit of the insertion of the rib. The bottle neck is closed by the line of stitching 62 and the function of the bottle neck is the same as that described in connection with the bottle neck of Figure 10. In the arrangement shown, the rib 65 is arranged at the outer side of the pocket or that side remote from the wearer. The rib 64 is tensioned so that its ends move from the wearer and its ends will not inconvenience the wearer, and these ends slidably engage behind the ends of the more flexible rib 65, preventing the ends of the rib 64 producing the unsightly bumps, as explained. The panel 61 extends beyond the opposite ends of the pocket 63, for a short distance, for affording attaching flaps 68, receiving the stitching 62, and this stitching also passes through the bottle neck 67, to close the same. The combined ribs 64 and 65 afford a rib having increased flexibility at its end.

In Figure 8, the body portion 20 of the girdle, is provided with an opening or space in its front, which is covered by a panel 67, which is preferably horizontally elastic but vertically non-elastic. This panel has elongated vertical pockets 68, woven integral therewith, said pockets having opposed sides 69. Near their ends, the pockets have enlarged portions 70 and 71. The top of the pocket 68 is closed, as shown at 72 and the lower end of the pocket 68 is provided with a bottle neck 73, similar to the bottle neck 51, Figure 1. The bottle neck 73 is closed by the stitching which secures the panel 67 to the body portion 20.

The numeral 74 designates a suitably stiff elongated rib, engaging at its upper end a relatively short rib 75, and at its lower end a relatively short rib 76, the rib 74 being separate from the ribs 75 and 76 and adapted to partake of relative movement with respect thereto. The wide rib 75 is passed upwardly through the bottle neck 73 and through the enlarged portion 71, through the pocket 68 into the enlarged portion 70. The rib 74 is passed through the bottle neck 73 and through the enlarged portion 71 into the pocket 68. The rib 76 is passed through the bottle neck 73 into the enlarged portion 71. After the ribs are positioned in the various portions of the pocket, they are attached or cemented to the wall or side of the pocket. The upper rib 75 has its outer face coated with a cement or adhesive material, as shown at 77, from its upper end to a point 78 and this adhesive securely bonds the rib 75 to the outer wall of the enlarged pocket portion 70. The outer face of the rib 74 is coated with an adhesive, as indicated at 79, throughout its entire length, and this adhesive securely attaches or bonds the rib 74 to the outer side of the pocket 68 and to the outer sides of the inner portions of the enlarged pocket portions 70 and 71. The lower rib 76 is coated with an adhesive, as shown at 80, extending from its lower end to the point 81, and this adhesive attaches or bonds the lower portion of the rib 76

16 to the outer side of the enlarged pocket portion 71. Any suitable form of adhesive may be employed. I have found that satisfactory results are obtained by having the ribs first coated with Celluloid which is allowed to dry and after the ribs are positioned within the pocket, a solvent of the Celluloid coating is applied to the fabric, and will penetrate the fabric and act upon the Celluloid coating, rendering the same 20 plastic so that it will adhere to the outer side of the pocket and its portions. However, any adhesive may be applied to the outer sides of the ribs, and while the adhesive is preferably applied to the outer sides of the ribs, it may be applied to the inner sides, or to both sides, but the overlapping portions of the ribs are free from adhesive so that such overlapping portions are free to have relative angular movements.

The advantage of this construction is that 25 contacting ribs 74 and 75 and 76 cannot become longitudinally displaced within their pockets nor is there any considerable relative longitudinal movement between the rib 74 and the end ribs 75 and 76, but since these ribs contact without being directly connected, not being cemented together, they have relative angular or turning movement, somewhat as if they were pivotally connected. By having the inner walls of the enlarged pocket portions 70 and 71 free from adhesive material, they remain freely elastic, and the ends of the ribs 74 can readily pivot or become angularly adjusted with respect to the ribs 75 and 76.

In Figure 11, I have shown a band 82, formed 30 of woven elastic material and longitudinally elastic and transversely inelastic. This band has spaced pockets 83 woven integral therewith. Each pocket has opposed sides 84 which are elastic. Each pocket is provided with a bottle neck 85 leading into the same, which is closed by a line of stitching 86, serving to attach the band to the article of apparel. Each pocket has a transverse web 87, integral with the opposite sides 84 and connecting them. The web 87 is preferably in 35 alignment with the bottle neck 85. The numeral 88 designates a U-shaped stiffening rib, adapted to be passed through the bottle neck 85, and having an opening 89 to receive the web 87. The web 87 serves to prevent the displacement of the rib 88 longitudinally of the band 40 50 55 60 65 70 75 80 85 90 95 100 105 110 115 120 125 130 135 140 145 150 155 160 165 170 175 180 185 190 195 formed closed and its opposite end provided with an elastic reduced bottle neck having a width smaller than the width of the pocket, the bottle neck forming a shoulder with the pocket, the fabric extending beyond one end of each pocket to form an attaching flap and the bottle neck being arranged near the free edge of the attaching flap, a stiffening rib within the pocket and having a width greater than the width of the bottle neck, a garment part arranged adjacent to the free edge of the attaching flap, and stitching securing the attaching flap to the garment part and also closing the bottle neck.

2. A section of fabric which is elastic in one direction and having spaced pockets formed integral therewith and arranged transversely of the direction of yield of the fabric, each pocket having opposed sides which are elastic in the direction of elasticity of the fabric, each pocket having one end closed and its opposite end spaced from the free edge of the fabric and provided with a reduced bottle neck which is elastic, the bottle neck being off-set laterally with respect to the longitudinal axis of the pocket and forming a shoulder therewith and extending to a point near the free edge of the fabric, the arrangement being such that when the free edge of the fabric is sewed to a garment part such sewing closes the bottle neck, and a rib for insertion within the pocket through the bottle neck and having prongs off-set laterally with respect to the longitudinal axis of the rib, the prongs being adapted to engage with the end walls of the pocket.

3. A sheet of fabric which is elastic in one direction and is provided with a plurality of spaced pockets formed integral with the sheet for receiving stiffening ribs, the pockets extending transversely of the direction of yield of the fabric, the fabric extending beyond one end of the pockets to provide an attaching flap, and tubular bottle necks formed integral with the attaching flap and extending longitudinally of the pockets and leading into the ends of the pockets and having a width less than the width of the pockets for providing shoulders, the bottle necks having their free ends spaced from the ends of the pockets, the arrangement being such that the ribs to be held within the pockets and having a width greater than the width of the bottle necks will have their ends held against displacement by the action of the elongated walls of the tubular bottle necks and the attaching flap may be secured to a garment part by a line of stitching spaced from the ribs.

4. A sheet of fabric which is elastic in one direction and is provided with a plurality of spaced pockets formed integral with the fabric to receive stiffening ribs, the pockets extending transversely of the direction of yield of the fabric, the

fabric extending beyond one end of the pockets to provide an attaching flap, and tubular bottle necks formed integral with the attaching flap and arranged exteriorly of the pockets and extending longitudinally of the pockets and leading into the ends of the pockets and having a width less than the width of the pockets for providing shoulders, the tubular bottle necks having their free ends arranged near the free edge of the attaching flap, the arrangement being such that the ribs to be held within the pockets and having a width greater than the width of the bottle necks will have their ends held against displacement by the action of the longitudinal walls of the tubular bottle necks and the attaching flap may be secured to a garment part by a line of stitching spaced from the ribs and also serving to close the bottle necks.

5. A sheet of fabric which is elastic in one direction and has a plurality of spaced pockets formed integral therewith, the pockets extending transversely of the direction of yield of the fabric, the fabric extending beyond the ends of the pockets, tubular bottle necks formed integral with the extension of the fabric and disposed transversely of the direction of yield of the fabric and leading into the ends of the pockets and having a width less than the width of the pockets for providing abrupt shoulders, the pockets having their opposite sides elastic and the spaces between the pockets being elastic and the tubular bottle necks having their opposite sides elastic and the spaces between the bottle necks being elastic, the free ends of the tubular bottle necks being spaced from the ends of the pockets, stiffening ribs held within the pockets, the ends of the stiffening ribs which engage the abrupt shoulders being at least wider than the bores of the tubular bottle necks, a garment part arranged adjacent to the extension, and stitching securing the extension to the garment part and passing through the bottle necks and spaced from the ribs.

6. A fabric section formed of longitudinally elastic material and having a pocket woven integral therewith, said pocket including sides and a partition web secured to said sides, the partition web having its free end spaced from the end of the pocket, said pocket also having an entrance opening which has a width less than the width of the pocket, and a stiffening rib for insertion within the pocket through the entrance opening, said stiffening rib having a width greater than the width of the entrance opening and also having an opening formed in one end thereof for receiving the partition web, the partition web when arranged within the opening serving to prevent displacement of the rib.

HENRY M. HERBENER.
